LIQUID FUEL COMBUSTION APPARATUS

Theodore B. Focke, Cleveland Heights, Ohio, assignee to Perfection Stove Company, Cleveland, Ohio, a corporation of Ohio

Application May 9, 1942, Serial No. 442,321

6 Claims. (Cl. 158—91)

This invention relates to improvements in liquid fuel burning apparatus of the class used for house heating or like purposes and typified by the inclusion of a burner bowl; and its main object is to provide apparatus of the aforesaid class and type that will operate efficiently and with a clean fire throughout a wide range between its lowest and highest rates of fuel consumption.

The present application is a continuation in part of one filed by me on May 17, 1938, Serial No. 274,175.

Burners of the kind referred to, preceding my invention, operated satisfactorily and efficiently only at a particular rate of fuel consumption. When ultimately adopted for use in furnaces, with automatic control systems, under certain conditions of which the burner was required to operate for long periods of time, sometimes for days and weeks, at very low or so-called pilot fire, these prior bowl type burners proved to be inadequate because when operating at low fire combustion was poor and carbon formation and deposit became excessive, frequently to the point of extinguishing the fire.

Further, these earlier burners were incapable of consuming much more than a gallon of fuel per hour—which is too little for house heating purposes under extreme conditions—without their having to be made undesirably large or else requiring the heating of the bottom portion of the burner bowl for vaporizing purposes to such an extent that the life of the bowl was very limited. By reason of my invention, as will hereinafter more fully appear, I am enabled to raise the rate of oil consumption approximately fifty percent without increasing the size of the burner bowl, and at the same time keep the bowl relatively cool.

A further defect or limitation in prior burners of the kind referred to, which rendered them impractical or unsatisfactory for the use to which my improved burner is especially well adapted, was the lack of a proper balance between the secondary air supply and the vapor volume at the various stages within the required range of operation. In these earlier burners, practically all secondary air for all stages of operation was admitted through a single slot or its equivalent, a single series of holes, and as a consequence, far too much air was admitted in the region of said slot or series of holes when the burner was operating at low fire. This excess of air produced considerable turbulence within the burner bowl which interfered with proper mixing of the oil vapors

and air. This resulted in the excessive carbon formation at low fire, hereinbefore mentioned.

It is a further purpose of my invention, therefore, to eliminate the foregoing difficulties by positively separating the secondary air required for low fire from that required for high fire whereby interference with low fire operation by the secondary air supply for higher fire purposes is avoided.

Another object of the invention is to provide a comparatively small bowl-type burner that is capable of a high rate of oil consumption, and that will function in a thoroughly satisfactory manner with practically complete combustion at all stages in a relatively wide range of operation.

My improved burner is of such character that the primary and secondary air supplies automatically adjust themselves to the different rates of oil feed throughout a complete range of operation, thereby to maintain a proper proportion of, or balance between, the air and vapor volumes at all times, the air apportionment being self-responsive to variations in vapor volume.

The foregoing objects and advantages, with others hereinafter appearing, are attained in the embodiments of the invention illustrated in the accompanying drawings wherein Fig. 1 is a vertical section through a combustion apparatus incorporating my improvements, the section being taken in offset planes as indicated by the line 1—1 of Fig. 2; Fig. 2 is a plan view of the burner bowl assembly disconnected and removed from the bottom of the combustion chamber shown in Fig. 1; Fig. 3 is a sectional detail showing a modified form of the annular element that defines the throat of the burner; Fig. 4 is a fragmentary plan view of the same; Fig. 5 is a central vertical section, somewhat schematic in character, through a further modified form of the invention, and Fig. 6 is a sectional plan view of the apparatus shown in Fig. 5.

In the liquid fuel burning apparatus illustrated fragmentarily in Figs. 1 and 2, the burner bowl is designated generally by the reference numeral 1, and it comprises an annular top wall 2, a peripheral wall 3, and a bottom wall 4. The top wall is formed with an inner horizontal portion 5 that is joined, through a shallow depending cylindrical portion 6, to an outer frusto conical portion 7, the rim of which is flat and is welded or otherwise secured to the flanged upper edge of the peripheral wall 3. At equally spaced points about its circumference, the wall 2 is formed with bays 8 for the purpose of increasing the radial dimension of the horizontal portion 5 at these

points; and the shallow cylindrical portion 6 is provided with air admitting openings 9, said openings occurring one within each of the bays 8 and one between each two adjacent bays. The peripheral wall of the bowl is provided with three circumferential series of perforations 10, 11 and 12.

Adjacent the front of the apparatus, the peripheral wall 3 has a relatively large lighting or clean-out opening 15 that is surrounded by a forwardly projecting flange 16, against the outer end of which is adapted to seat a gasket 17 of suitable non-inflammable packing material carried within the channeled edge portion of a member 18 that is swiveled, through a pivotal element 19, to the inner end of a plug 20. The enlarged outer end 21 of this plug fits within a sleeve 22 that surrounds the flange 16 and is secured at its inner end to the burner bowl. The enlarged end 21 of the plug 20 is notched at diametrically opposite points for the passage of projections or rollers that extend inwardly from the sleeve 22, one of such notches being shown at 23 in Fig. 1, and the corresponding projection or roller at 24. The front edge of the enlargement of the plug is cut away on a taper to one side of each of the notches thereby to provide a cam portion 25 for engagement with the corresponding projection or roller, these parts cooperating to press the plug inwardly so as to seal the joint between the gasket 17 and the flange 16 when the plug is turned clockwise by means of its handle 26.

The bottom wall 4 of the bowl is slightly dished, and at its center is provided with an opening in which is secured the lower end of an air tube 30 that is surmounted by an air distributor or nozzle 31, the latter being shown as having perforations 32 in its top. Welded or otherwise secured to the exterior of the bottom wall 4 are insulating shields 33 and 34, having central openings that align with the air tube 30; and liquid fuel is adapted to be delivered to the burner bowl through a supply pipe 35 that passes through openings in the shields 33 and 34 and in the wall 4, the pipe being welded or otherwise secured to said wall with a leak-proof joint.

Disposed above and in spaced, parallel relation to the horizontal portion 5 of the top wall 2 is a ring-like member 36 whose inner edge is flanged upwardly at 37. Outwardly beyond an adjacent horizontal portion, said member flares upwardly at a slight angle and joins, through a vertical portion 38, a relatively wide horizontal peripheral flange 39. The member 36 is rigidly secured to the top wall 2 by posts 40 of narrow and long cross-sectional shape, as indicated in Fig. 2, the posts being arranged with their longer cross sectional dimension radial to the bowl. This is for the purpose of minimizing resistance to the flow of air inwardly between the wall 2 and member 36 and for obviating voids of appreciable size in the air stream inwardly of the posts. The upper and lower ends of the posts 40 are projected through slots in the member 36 and wall 2, respectively, and are fastened to said member and wall desirably by welding.

An annular element 42, preferably of relatively thin steel having the quality to effectively withstand the heat to which it is subjected, has its upper cylindrical end 44 fitted within the flanged edge 37 of the ring-like member 36, the parts being secured together as by welding. From its cylindrical end 44 the element converges downwardly in frusto conical form, as shown at 45, and joins a shallow vertical or upstanding wall

designated 46, the element below said upstanding wall being flanged outwardly over the inner edge portion of the wall 2 to which it is secured, preferably by welding. The upstanding wall is provided with a circumferential series of relatively closely spaced perforations or openings 47, while the frusto conical or generally outwardly and upwardly extending portion 45 is provided with an annular series of perforations or openings 48 shown as considerably larger than the openings 47 of the former series. It is the structure or element comprising the upstanding wall and the wall portion that extends generally outwardly and upwardly therefrom that constitutes the neck of the burner, said upstanding wall defining the more restricted part or throat. In the present instance, the number of holes is the same in both series, but those designated 48 of the upper series are materially larger than the ones designated 47 of the lower series. It is the fact that the aggregate area or capacity of the perforations or openings in the generally outwardly and upwardly extending portion of the structure that constitutes the neck of the burner is materially greater than the aggregate area or capacity of the perforations or openings in the upstanding wall of said structure that characterizes or distinguishes the species of the invention to which the present continuation application is directed.

Surrounding the burner bowl is an air compartment 50 enclosed by a peripheral wall 51, a circular bottom wall 52 and an annular top wall 53. This latter wall has its contracted upper end fitted over and secured, as by welding, to the vertical portion 38 of the ring-like member 36, while its flared lower end terminates in a shallow cylindrical flange that fits within the upper edge of the peripheral wall 51 and is fastened thereto, as by screws 54. The bottom wall 52, apertured to accommodate the supply pipe 35, is provided with an opening 55, surrounded by a depending flange to which is connected an air duct 56 that leads from a suitable air impelling or supply means, such as a fan or blower.

The combustion chamber 50 is enclosed by a drum 61 within the lower end of which is fitted an annular bottom wall 62, said wall extending from its flanged outer edge, where it is welded or otherwise fastened to the drum, generally downwardly and inwardly to a horizontal portion 63 whose inner edge is surrounded by a depending flange 64. When the burner bowl assembly is applied to the bottom wall of the combustion chamber, the flange 64 is received within the cylindrical portion 38 of the ring-like member 36, and the peripheral flange 39 of said member engages the underside of the horizontal portion 63 of the wall 62. Said peripheral flange and wall portion are provided with aligned openings (those of the flange being designated 65 in Fig. 2) through which bolts 67 are downwardly projected and have lock washers 68 and nuts 69 applied to their lower ends.

Liquid fuel from a suitable source is fed to the bowl 1 through a fuel feeding system of which the pipe 35 forms a part. The system includes means for varying the quantity of fuel delivered to the bowl for the purpose of producing different sized fires from pilot to high. By means of an automatic control system, involving a so-called room thermostat, the fire may be regulated to maintain a given temperature within narrow limits in the general vicinity of the room thermostat.

For example: I may employ in connection with my liquid fuel burning apparatus, the fuel system disclosed in Patent 2,247,689, dated July 1, 1941; and I have shown a part of such a system associated with the apparatus in Fig. 1. Communicating with the bowl 1 through the pipe 35 is an outlet compartment 70 of a vessel 71. Said outlet compartment 70 is set off from a reservoir part 72 by a barrier or partition 73. Liquid fuel is supplied to the reservoir part 72 through a pipe 75 from means (not shown); such as a float chamber, that serves to maintain a liquid level in the reservoir part 72 at about the elevation indicated by the broken line *a*. The float chamber, as well as the automatic control system presently to be referred to but not illustrated herein, are fully disclosed in the patent aforesaid.

Pivots supported above the barrier or partition 73 are trough-like buckets or dippers 76, 77 and 78, the same being arranged to dip into the fuel supply in the reservoir part 72 and transfer a quantity of the fuel to the outlet compartment 70 as the buckets are oscillated. The mechanism by which such action is imparted to the buckets or dippers comprises a gear 80 that is rotatably supported on a stub shaft 81 that projects from the adjacent upwardly extended side wall of the vessel 71. Said gear carries a crank pin 82 that is connected, through a link 83, with the bucket 76. The gear 80 meshes with and is driven by a pinion 85 on a shaft 86 which, as disclosed in the aforesaid patent, is the shaft of a small electric motor that is attached to the side of the vessel 71. Mounted on the shaft 86 beyond the pinion 85 is a double crank 87, the diametrically opposed pins of which are designated 88 and 89. These respective crank pins extend freely through slots in links 90 and 91, the former being attached to the dipper or bucket 77 and the latter to the dipper or bucket 78.

Secured to and depending from an overhanging portion 92 of the upwardly extended end wall of the vessel 71 are latch members 93 and 94 for holding engagement, respectively, with rearward extensions of the dippers or buckets 77 and 78, respectively. The latch members 93 and 94 are actuated by the automatic control system illustrated and described in the beforementioned patent.

To describe, briefly, the operation of the fuel feeding means, it may be said that the shaft 86, and consequently the pinion 85 and gear 80, are constantly driven by the motor (not shown). By reason of its connection, through the link 83 and crank pin 82 with the gear 80, the bucket 76 is constantly actuated to intermittently transfer quantities of fuel from the reservoir parts 72 of the vessel 71 to the outlet compartment 70 from whence the liquid fuel flows to the burner bowl 1 through the pipe 35, it being obvious that a quantity of fuel would be present in the outlet compartment to an elevation at least as high as the outlet of the pipe 35. Thus, at all times, sufficient fuel is fed to the burner bowl to sustain low or pilot fire. As long as nothing higher than pilot fire is required, the dippers or buckets 77 and 78 are held inactive—that is, in elevated position, by the latch members 93 and 94, the crank pins 88 and 89 idling within the slots of the respective links 90 and 91 as the double crank 87 rotates. When conditions are such that intermediate fire is required in order to maintain a given temperature at the room thermostat, the system functions in the manner described in said patent to retract latch member 93, thereby to

release the dipper or bucket 77 and throw it into action through its driving connection with the double crank 87. Should the demand for heat exceed the output of the burner at intermediate fire, the latch member 94 will be retracted so as to release the dipper or bucket 78 to the action of the crank mechanism and cause it to increase the amount of fuel fed to the burner sufficiently to produce high fire. As the demand for heat decreases, the buckets 78 and 77 are thrown out of operation by the projection of the latch members 94 and 93 beneath the extensions of said buckets.

A modified form of the element or structure that constitutes the neck of the burner is illustrated in Figs. 3 and 4, where the element is designated generally by the reference numeral 95. The upstanding wall 96 thereof is provided with a series of perforations or openings 97, which may correspond in size and spacing to the perforations or openings 41 of the previously described form of the element. In the present case, two series of openings are made in the generally upwardly and outwardly extending portion 98, one such series being composed of perforations or openings 99, that may be slightly larger than the perforations or openings 97 of the previous series, while the second and outer series of said portion 98 is composed of perforations or openings 100 that may be still larger than those in the second mentioned series. Here, again, the aggregate area or capacity of the perforations or openings in the generally upwardly and outwardly extending portion of the element is materially greater than that of the perforations or openings in the upstanding wall that defines the throat of the burner.

Figs. 5 and 6 rather diagrammatically illustrate an embodiment of the invention wherein the inner edge of the top wall 105 of the burner bowl 106 is connected, through a neck-like structure designated generally by the reference numeral 107, with the annular bottom wall 108 of the combustion chamber 110, the peripheral wall of the bowl 106 being provided with primary air holes 109. The combustion chamber 110 is enclosed within the upper portion of a cylindrical drum 111 whose lower end is extended well below the bottom wall 108 of said chamber and beyond the bottom of the burner bowl where it is closed by a circular plate 113. This plate is fitted into the lower end of said drum and defines the bottom of an air compartment 114 that surrounds the burner bowl and is provided, in said plate 113, with an opening 115 through which said compartment communicates with an air supply duct 116. A baffle plate 117 is supported by brackets 118 above the opening 115 to shield the burner bowl from the chilling effect of incoming air. Liquid fuel is supplied to the burner bowl through a pipe 119.

The previously mentioned neck-like structure 107 consists of an upstanding wall 120 that defines the throat of the burner, and a generally outwardly and upwardly extending stepped portion that merges with the bottom wall 108 of the combustion chamber, such part being designated 121. The upstanding wall 120 is provided with a series of perforations or openings 122, while the upwardly and outwardly extending portion 121 is provided with series of openings 123 that are arranged to direct air upwardly into the combustion chamber.

As in the former cases, the aggregate area or capacity of the openings in the generally up-

wardly and outwardly extending portion of the structure that constitutes the neck of the burner is considerably greater than that of the series of perforations or openings in the upstanding wall of said structure.

Before describing the operation of the apparatus, I may explain with particular reference to the embodiment of the invention illustrated in Figs. 1 and 2 that, by reason of the fact that the combustion chamber is in constant communication with the flue, according to the customary installations of such apparatus, and the additional fact that air is supplied to the compartment 50 through the duct 56, as by forced draft means, if desired, air is constantly entering in limited quantity through the primary air holes 10, 11 and 12, in the peripheral wall of the burner bowl and through the openings 32 of the air distributor 31, and in much greater amount through the series of perforations or openings of the structural part or element 42 that constitutes the neck of the burner. It may be pointed out, also, that the natural draft of the flue varies directly in accordance with changes in its temperature so that the draft is greater at high fire than at low; and when forced draft means are provided for impelling air through the duct 56 and compartment 50, the action of such means is usually accelerated as the fire increases. However, because the aggregate area or capacity of the perforations or openings 41 in the upstanding wall 46 of the element 42 is very considerably less than that of the perforations or openings in the outwardly and upwardly extending portion 45 of said element, the volume and force of the air that enters through the former series is very much less than the volume and force of the air entering through the latter series.

In considering the operation of the apparatus, it will be assumed that fuel is being fed to the burner bowl at a rate to sustain operation at low or pilot fire, as by the action of the dipper or bucket 76, exclusively. With the fuel ignited—which may be accomplished by removing the plug 20 from the opening 15 and introducing suitable igniting means therethrough after which the plug is replaced and the opening tightly sealed in the manner previously described—vapors are generated within the bowl and rise therein and mix with the air admitted through the primary air holes 10, 11 and 12 and with the air issuing from the holes 32 of the air distributor 31, thus being conditioned for combustion when it reaches the curtain of air within the throat defined by the upstanding wall 46. Ample secondary air being thus added to the mixture, it completely burns and presents the appearance of a rather blue sheet of flame extending horizontally across the throat in slightly spaced relation to the upstanding wall 46. The perforations or openings in said upstanding wall are spaced closely enough together to cause the streams or jets of air issuing therefrom to merge a short distance inwardly from said wall. This action, I find, is much superior to that produced by a continuous slot in that it effects a thorough mixing of the air and vapors immediately adjacent said upstanding wall whereas, with a slot, the continuous sheet of air issuing therefrom has a tendency to obstruct, rather than to effectively mix with, the vapors. The air in excess of that required for producing complete combustion and maintaining the gentle curtain across the throat at pilot fire, issues through the series of perforations or openings in the outwardly and upwardly extending

portion of the element 42 into the combustion chamber 60.

When, because higher fire is required, additional fuel is fed to the burner bowl, as through the action of either or both of the dippers or buckets 77 and 78, the volume of vapors generated in the bowl will increase to such an extent that the air entering through the primary air holes 10, 11 and 12 and through the holes 32 of the air distributor will be only a small percentage of that required to mix with and convert the present quantity of vapors into a combustible gas. The deficiency in the primary air supplied through said holes, under the present conditions, will be compensated for by the air entering across the throat of the burner through the perforations or openings 41. In other words, when the increased volume of vapors reaches the throat of the burner it is rendered combustible by the addition of further primary air thereto and burns as it enters the atmosphere of secondary air admitted to the combustion chamber through the perforations or openings in the outwardly and upwardly extending portion of the element 42.

When the apparatus is in operation and changes from low to higher fire, I have observed that the increased volume of vapors forces the curtain of flame that extends substantially horizontally across the throat of the burner at low fire upwardly and back, the flame assuming the effect of a rising column as the fire increases. The foregoing action of the flame is enhanced by the increased amount of air issuing through the openings 32 of the air distributor 31, caused by the acceleration of the flue draft, or such plus the increase in the air supply through the duct 56, as hereinbefore pointed out. The quantity of air entering through the primary air holes and through the perforations or openings in the element 42 is likewise increased, the amount of secondary air entering through the perforations or openings 48 in the outwardly and upwardly extending part of said element being ample to insure practically complete combustion under the higher fire conditions.

Furthermore, because combustion is confined to the region of the burner throat at low fire, and thereabove at higher fires, the bottom portion of the bowl never becomes injuriously hot.

From the foregoing, the operation of an apparatus involving the modified form of neck structure illustrated in Figs. 3 and 4, and that of the modified form of the invention illustrated in Figs. 5 and 6, will be readily understood.

Having thus described my invention, what I claim is:

1. Liquid fuel burning apparatus of the class used for house heating or like purposes, the same comprising a combustion chamber, a burner bowl situated below said chamber, a structure in the form of a short wide neck through which the bowl and chamber communicate, the same including an upstanding part of slight vertical extent adjacent the bowl and a part that extends generally outwardly and upwardly therefrom to where it joins the bottom of the combustion chamber, the upstanding part being provided with relatively small closely spaced perforations throughout the circumference thereof and the outwardly and upwardly extending part having closely spaced perforations throughout its circumference and whose aggregate capacity is materially greater than that of the perforations in said upstanding part, the first mentioned perforations serving to admit a limited amount of air from a surrounding air

space horizontally inwardly across the throat and the second mentioned perforations serving to admit air from said space in considerably greater amount generally upwardly into the combustion chamber, the bowl being provided with openings about its peripheral wall for admitting air from the aforesaid space to the bowl in comparatively small amount, and means for delivering liquid fuel to the bowl in varying quantities for producing low and relatively higher fires.

2. Liquid fuel burning apparatus of the class used for house heating or like purposes, the same comprising a combustion chamber having a bottom wall provided with a relatively large opening, a burner bowl having a top wall spaced below said bottom wall and provided with an opening materially smaller than the beforementioned opening and in substantially axial alignment therewith, an element in the nature of a relatively thin short wall connecting the edges of said top and bottom walls about said openings and having an upstanding part adjacent the top wall of the burner bowl and a part extending generally outwardly and upwardly thereabove, the upstanding part being provided with a series of relatively small closely spaced perforations throughout its circumference and the outwardly and upwardly extending part also having closely spaced perforations throughout its circumference and whose aggregate capacity is several times that of the perforations of the upstanding part, the perforations of said upstanding part serving to admit a limited amount of air from a surrounding air space horizontally inwardly across the throat defined by said part and, due to the close spacing of said perforations, to cause the air jets produced by said perforations to merge a short distance inwardly of said upstanding part into a continuous sheet throughout the central region of the throat, the perforations of the outwardly and upwardly extending part serving to admit additional air in relatively greater amount generally upwardly into the combustion chamber, the bowl being provided with openings about its peripheral wall for admitting air from the aforesaid air space in comparatively small amount, and means for delivering liquid fuel to the bowl in variable quantity for producing relatively low and higher fires.

3. Liquid fuel burning apparatus of the class used for house heating or like purposes, the same comprising a combustion chamber having a bottom wall provided with a relatively large circular opening, a burner bowl having a top wall spaced below said bottom wall and provided with a circular opening materially smaller than the beforementioned opening and in substantial axial alignment therewith, an annular element in the nature of a relatively thin short wall connecting the edges of said top and bottom walls about said openings and having an upstanding part adjacent the top wall of the burner bowl and a frusto-conical part flaring outwardly and upwardly therefrom, the upstanding and frusto-conical parts of said element being provided each with a series of closely spaced perforations throughout the circumference of the element, the aggregate capacity of the perforations of said upstanding part being materially less than that of the perforations of the frusto-conical part, said series of perforations of the upstanding part serving to admit a limited amount of air from a surrounding air space horizontally inwardly across the throat defined by said part, and the perforations of the frusto-

conical part serving to admit additional air in relatively greater amount upwardly and inwardly into the combustion chamber, the bowl being provided with openings about its peripheral wall for admitting air from the aforesaid space in comparatively small amount, and means for delivering liquid fuel to the bowl in variable quantity for producing low and relatively higher fires.

10 4. Liquid fuel burning apparatus of the class used for house heating or like purposes, the same comprising a combustion chamber, a burner bowl situated below said chamber, a structure in the form of a short wide neck 15 through which the bowl and chamber communicate, the same including an upstanding part of slight vertical extent defining a throat immediately adjacent the bowl and a part that extends generally outwardly and upwardly therefrom to where it joins the bottom of the combustion chamber, the upstanding part being provided with a series of relatively small closely spaced perforations throughout the circumference thereof and the outwardly and upwardly extending part having a plurality of series of closely spaced perforations throughout its circumference, the holes of the different series becoming larger as the series progresses outwardly, the aggregate capacity of the perforations in 20 the outwardly and upwardly extending part being several times greater than that of the perforations in the upstanding part, the first mentioned series of perforations serving to admit a limited amount of air from a surrounding air 25 space horizontally inwardly across the throat and the other series of perforations serving to admit air from said space in considerably greater amount generally upwardly into the combustion chamber, the bowl being provided with openings about its peripheral wall for admitting air from the aforesaid space to the bowl in comparatively small amount, and means for delivering liquid fuel to the bowl in varying quantities for producing low and relatively higher fires.

45 5. Liquid fuel burning apparatus of the class used for house heating or like purposes, the same comprising a combustion chamber having a bottom wall provided with a relatively large circular opening, a burner bowl having a top wall spaced below said bottom wall and provided with a circular opening materially smaller than the beforementioned opening and in substantial axial alignment therewith, an annular element in the 50 nature of a relatively thin short wall connecting the edges of said top and bottom walls about said openings and having an upstanding part adjacent the top wall of the burner bowl and a frusto-conical part flaring outwardly and upwardly therefrom, the upstanding part being provided with a series of closely spaced perforations throughout its circumference, and the frusto-conical part having an inner and an outer series of closely spaced perforations throughout the circumference of the element, the aggregate capacity of the perforations of said upstanding part being materially less than that of the perforations of the frusto-conical part, the bowl being provided with openings about its peripheral wall, and means for delivering liquid fuel to the bowl in variable quantity for producing low and relatively higher fires.

6. Liquid fuel burning apparatus of the class used for house heating or like purposes, the same comprising a combustion chamber, a burner

bowl situated below said chamber and having primary air holes in its peripheral wall, a structure in the form of a short wide neck through which the bowl and chamber communicate, said structure including an upstanding part of slight vertical extent adjacent the bowl and a part that extends generally outwardly and upwardly therefrom in the form of steps having substantially horizontal portions, the upstanding part being provided with relatively small closely spaced perforations throughout the circumfer-

ence thereof and said horizontal portions of the steps being provided with closely spaced perforations thereabout, the aggregate capacity of the perforations of said horizontal portions being materially greater than that of the perforations in said upstanding part, and means for delivering liquid fuel to the bowl in varying quantities for producing low and relatively higher fires.

THEODORE B. FOCKE.
